SPACING BALANCE WHEEL FOR DISK HARROWS AND DISK PLOWS

Charles Opolo, Culver City, Calif.

Application April 13, 1936, Serial No. 74,138

12 Claims. (Cl. 97—220)

My invention relates to balance wheels used in connection with disk harrows and disk plows in order to secure a uniform depth of cut by the assembly of disks.

5 In the ordinary use of disk harrows or disk plows which are made with a dish type of disk, concave on one side and convex on the other, it is found that the end of the harrow toward which the concave sides face digs deeper than the opposite end of the assembled disks. These 10 disks are usually assembled on a shaft, and therefore one end tends to cut deeper than the other although the assemblage of disks is mounted in a suitable frame. It has been customary to overcome this difficulty by loading weights on the 15 frame of the machine toward the end of the assemblage of disks which has the shallow cut, and therefore force this end deeper in order to secure a uniform depth of harrowing or plowing.

20 An object and feature of my invention is in providing wheels of different weight which may be built into an assemblage of the disks whereby a heavy solid wheel may be located adjacent the end of the shaft carrying a large number of disks. If this is the end which normally would have a 25 shallow cut, at the opposite end which would normally dig deep a hollow wheel is secured between the disks and thus adds a lesser weight to the end which normally cuts deeper. All of the 30 wheels are of the same diameter and function to limit the depth of cut as manifestly when the wheels roll on the surface of the ground they limit the depth of cut.

35 A more detailed object and feature of my invention is in the attachment of the wheels to the ordinary spacing spools between the disks. These spools are usually mounted on a shaft or rod between adjacent disks and operate to space the disks the desired distance apart. In certain forms 40 of my invention I attach the wheels directly to the spools and in this manner can use the spools to build up the desired size of wheel. In other cases the wheel and the spool are made as one unit which may be solid where it is desired to apply considerable weight or having a considerable sized hollow space which may be filled 45 with light material in order to give a wheel of a lesser weight.

50 A further detailed feature in forming the light weight wheels is in forming these in two half sections, each having a tread and a marginal rim forming in effect a cup except for the opening at the rim. These rims are then fitted over flanges on a spacing spool to bring the edges of the tread 55 together. A weld is made at the joint, thereby

forming a wheel with a cylindrical tread of substantially the same length as that of the spacing spool.

5 Another object and feature of my invention relates to a scraper for use with the supporting wheels and also to scrape the adjacent disks. In this case an arm locates the scraper in relation to the frame, and this has a blade for scraping the cylindrical surface of the wheel and a secondary curved blade for scraping the inside or 10 convex surface of a disk.

15 My invention is illustrated in connection with the accompanying drawing in which:

Figure 1 is a longitudinal section through an assembly of disks mounted on a shaft and may be 15 considered as taken on section line 1—1 of Figure 4 in the direction of the arrows omitting the scrapers.

20 Figure 2 is an enlarged section of one of the light weight wheels, this being formed hollow and shown on the right hand end of Figure 1. In Figure 2 the spool is separated from the shaft.

25 Figure 3 is an end elevation taken in the direction of the arrow 3 of Figure 2.

Figure 4 is a plan of part of a disk harrow.

30 Figure 5 is a partial elevation taken in the direction of the arrow 5 of Figure 4 showing in particular the scraper, portions of the disks being broken away.

35 Figure 4 shows part of a frame 11 which may be of any suitable type such as is employed in disk harrows or disk plows. There is a shaft or axle 12 on which are mounted a number of spacer spools 13 separating the disks 14. An end washer 15 forms the housing for a head 16 of the axle 35 and at the opposite end there is a washer 17 on which bears the nut 18 for clamping the assembly of spacer spools and disks. At certain of these spools there is a bearing 19 to which is secured a side bar 19a of the frame 11.

40 My invention comprehends using weighting wheels designated by the assembly numeral 20. Where it is desired to have a heavy wheel this is preferably formed as a casting indicated at 21. This casting has a convex end 22 and an opposite concave end 23 to conform to the shape of adjacent disks. There are also offset sides 24 and 25 forming a clearance from the disks. The peripheral tread 26 is wide and cylindrical. This form of cast wheel has a central core to accommodate 50 the axle 12 being made of the same internal shape as the spools this being shown in the present illustration as square in cross section.

55 A lighter type of weighted wheel is illustrated at 30. This is also formed preferably of a cast-

ing but in this case there is a deep recess 31 formed from one end leaving a central hub 32 the cylindrical tread 33 on the outside. At the end of the hub there is a flange 34 having a concave end face to conform to the shape of the adjacent disk. This leaves an annular opening 35. In order to prevent dirt from filling this space it is preferable to initially fill this space before the assembly of the wheel with the disk 10 harrow with light material such as ground cork which may be held in place by a plastic composition indicated at 36 of Portland cement or other suitable covering. This construction therefore has the wheel formed with a relatively heavy 15 end portion 37, the other portion being light. Manifestly as the recesses 31 may be made of a greater or lesser depth, weights of different sizes may be produced.

A lighter type of wheel is illustrated at 40. 20 In this case there are two cup like devices 41 and 42 formed preferably of sheet metal placed to shape, each of which has a cylindrical wall indicated at 43 and 44 butting at a joint 45 which follows the circumference. Each of these 25 portions has an inturned rim 46 and 47. The rim 46 is flared outwardly and the rim 47 extends inwardly.

The spacer spool 50 has a hub section 51 with a flange 52 at one end convex on its end surface 30 53 and has an annular shoulder 54 with an outwardly projecting rim 55. The inturned rim 46 fits against the shoulder 54 and the rim 55 end is secured by an annular weld 56.

At the opposite end of the spool there is a flange 57 having an annular shoulder 58 and an outwardly extending rim 59. This rim is shaped with a slope to engage the inside surface of the inturned rim 47, such rim likewise fitting against the shoulder 58 and being secured by a weld 60. A circumferential weld 61 secures the two cups together at the joint 45. In this manner a hollow wheel is assembled on one of the spacer spools. This wheel thus is much lighter 40 in weight than the solid cast wheels or the wheels with the recess and is intended to be placed in the disk assembly adjacent the end which sinks most deeply.

In the operation of my invention it will therefore be seen that as one end of the disk assembly may be weighted with a solid or heavy wheel an intermediate section with a lighter cast wheel and the end which cuts deeper with the light hollow wheel that these may be projected 50 so that the disk harrow as a whole will cut to a uniform depth. My invention also has another function in that the wheels limit the depth of cut of the disks for manifestly when the periphery of the disks engage the surface of the soil the depth of cut is limited. This is of material advantage when working in soft soils. Manifestly when much work is to be done in such soils the hollow wheels may be used throughout instead of having any of the wheels weighted by being 60 formed solid or partially solid.

The machine is provided with scrapers designated by the assembly numeral 70, each of which has a long and substantial arm 71 secured to one of the cross frame members 72. The arm bends 70 downwardly towards the wheels and has a horizontal scraping edge 73 adapted to scrape the periphery of each of the wheels and on the sides there is a curved scraper 74, this scraper engaging the concave side of an adjacent disk. By 75 this construction as the disks and the wheels

rotate as a unit each of the wheels and a disk adjacent thereto are scraped of mud or soil adhering to the wheel or to the disk or both.

Various changes may be made in the details of the construction without departing from the spirit or scope of the invention as defined by the appended claims.

I claim:

1. In a disk harrow in which a frame forms a mounting for an axle having harrowing disks 10 mounted on the axle with a spacing means for the disks combined with weighting wheels forming part of the spacing means, certain of said wheels being substantially solid to give a considerable weight to increase the cut of the disks adjacent 15 the solid wheel and other wheels being substantially hollow, the periphery of the wheels being operative to limit the depth of the cut of the disks.

2. In a disk harrow as described in claim 1, 20 there being other wheels with a cylindrical periphery and having a hollow space extending from one end of the wheel, said wheels with the hollow space being lighter than the substantial- 25 ly solid wheels.

3. In a disk harrow in which a frame forms a mounting for an axle having harrowing disks mounted thereon, the disks being separated by spacer spools combined with certain of the spacer 30 spools being constructed in the form of wheels with a cylindrical periphery, said wheels being placed longitudinally of the shaft to increase the weight to thereby cause a relatively deep cut by the disks, certain of the wheels being solid except for an opening to accommodate the shaft, other wheels having a hollow space whereby 35 there is a difference of weight between the solid and the hollow wheels, both the solid and the hollow wheels being of the same diameter to regulate the depth of cut of the disks.

4. In a disk harrow having a frame, a shaft mounted in the frame and having harrowing disks thereon, said disks being spaced by spacing spools, one of said spools being enlarged to form a solid wheel with a cylindrical periphery, another of said spools having a wheel with a cylindrical periphery and a connecting means between the periphery and the ends of the spool to thereby form a substantially hollow wheel, the diameters of both wheels being equal.

5. In a disk harrow as described in claim 4, another spool being enlarged to form a wheel with a solid periphery and having a hollow space extending from one end in order to form a wheel 50 having a weight intermediate between the solid wheel and the hollow wheel.

6. In a disk harrow as described in claim 4, the spools having an end contact with adjacent disks and the portion of the wheel extending from the spool to the periphery being spaced at its 60 ends from the adjacent disks.

7. In a disk harrow having a shaft, a plurality of disks thereon separated by spacing spools, one of said spools having one concave and one convex end to fit with adjacent disks and having a central enlargement of metal, said enlargement having a cylindrical periphery and forming a weighting wheel, the ends of the wheel being concave at one end and convex at the other, but 65 spaced from the adjacent disks.

8. In a disk harrow as described in claim 7, the wheel having a hollow section with an annular opening leading thereto adjacent one end of the spool.

9. In a disk harrow having an axle with disks mounted thereon separated by spacing spools, one of said spools having a central hub section and having flanges at opposite ends, one of the 5 ends being concave and the other convex to fit the adjacent disks, a wheel having a cylindrical periphery and having an inturned rim at each side, each rim being secured to one of the flanges of the spool, the wheel being substantially hollow 10 from the hub of the spool to its periphery and being operated to limit the depth of cut of the disks.

10. In a disk harrow having a shaft with a plurality of disks thereon separated by spacing 15 spools, one of the spools having a central hub with flanges at each end, the flanges having annular shoulders with annular rims extending outwardly therefrom, a wheel formed of two cup-like structures, each having a cylindrical periphery abutting at a circumferential joint and each 20 having an inturned rim engaging the shoulder

and rim at the ends of the spool, the wheel being secured to the spool by welds adjacent the shoulders and the two cup structures being secured by a weld at the circumferential joint.

11. In a disk harrow as claimed in claim 4, a 5 scraper supporting arm secured to the frame, a first scraper blade connected to the arm and positioned to scrape the periphery of one of the wheels, a second scraper blade having a convex edge positioned to scrape the concave side of an 10 adjacent disk.

12. In a disk harrow the combination of a frame, an axle having a plurality of disks thereon, a wheel having a cylindrical periphery positioned between two adjacent disks, a scraper arm 15 secured to the frame, a first blade thereon having a straight edge positioned to scrape the periphery of the wheel, the arm having a second blade having a convex edge positioned to scrape the concave side of an adjacent disk. 20

CHARLES OPOLO.
